CLAIM

I claim the ornamental design for a barbecue grill, as shown and described.

DESCRIPTION

FIG. 1 is a perspective view of a barbecue grill showing my new design;

FIG. 2 is a top plan view thereof;

FIG. 3 is a bottom plan view thereof;

FIG. 4 is a front elevational view thereof;

FIG. 5 is a rear elevational view thereof;

FIG. 6 is a perspective view in use with a possible stand; and,

FIG. 7 is a perspective view in use with a possible alternate stand.

The details shown in broken lines in FIGS. 1,2 and 4-7 are for illustrative purposes only and form no part of the claimed design.
